UNITED STATES PATENT OFFICE.

ALBERT E. DION AND CHARLES W. BALL, OF OTTAWA, ONTARIO, CANADA.

ELECTRIC-CURRENT CONTROLLER.

No. 877,705.

Specification of Letters Patent.

Patented Jan. 28, 1908.

Application filed November 19, 1906. Serial No. 344,097.

To all whom it may concern:

Be it known that we, ALBERT E. DION and CHARLES W. BALL, citizens of the Dominion of Canada, and residents of Ottawa, county 5 of Carleton, Province of Ontario, Canada, have invented new and useful Improvements in Electric-Current Controllers, of which the following is a specification.

The object of the present invention is to 10 enable electric corporations to have automatic control of the quantity of current they contract to supply. This is accomplished by a certain arrangement of resistance, so introduced in the main circuit that in the 15 event of an attempt to draw from said circuit more than the load contracted for, the voltage will be intermittently reduced during all the time the excess of load is maintained. If our device is used to control a predetermined 20 number of electric lights, any attempt to add one or more lights in excess, these lights will intermittently disturb the voltage in the circuit, and render the lighting unbearable, on account of the lights being 25 dimmed and glowed in comparative rapid interval.

Our mechanism is hereinafter described in the following specification, which must be read in connection with the drawings annexed, 30 and in which similar letters of reference denote the same parts throughout.

Figure 1 represents in front view the complete controller excepting the cover. Fig. 2 is a section on line y, y , Fig. 1.

Upon a suitable base a the whole mechanism is mounted, this base has a cover not shown, which may be of metal or glass, b are perforated lugs to fasten the base, c' is a suspending ear, $m m'$ are the binding screws for 40 the main circuit wires, m being the leading in binding screw, and m' the outlet.

In the following description, we will consider the controller connected and in actual use on a normal load. As previously said, 45 the current enters at m , and passes to the binding screw A , then through the wire 1, the solenoid B , the flexible looped wire 2, the plunger rod 3, the mercury 4, the contact spring 5, the binding post 5', the wire 6, the 50 binding screw E , to outlet binding screw m' . We will now describe the solenoid and its movements, B is the coil shown in section in Fig. 2, D is the armature, consisting preferably of a hollow iron tube, to the upper end 55 of the armature, D , is rigidly fastened the bar g , which extends an equal length on both

sides of the armature, this bar is perforated vertically at $U. U.$ and horizontally at $V. V.$ the solenoid is mounted between a base plate s , and a top plate t , these plates are bound fast to the solenoid ends by the rods k , the base plate s carries a mercury cup C , positioned centrally, and below the solenoid coil, the same plate carries also a binding post 5', and a binding screw 7, the top plate t carries 60 two upright posts c , positioned as shown, the uprights serve as guides for the bar g , because they extend through the perforations $U. U.$ of the same, the top ends of the upright posts c , are bifurcated, mounted in this 65 bifurcation are the beams $d. d.$, said beams are fulcrumed at x' , each beam d carries an adjustable weight H , this weight is made to slide longitudinally on the beam, and is fixed thereto by a set screw as 12. The beams 70 $d. d.$ are connected at their outer ends to the bar g of the solenoid armature by means of links $e. e.$, and at their inner ends to the contact plunger 3, by links $f. f.$ at the point n , by this connection, it will be evident that the 75 movement of the beams is synchronous with that of the solenoid armature D , when this armature plunges deeper in the solenoid, the outer ends of the beams receive a corresponding lowering, the inner ends are raised 80 and as the contact plunger 3 is connected thereto, it will be raised completely or partly 85 out of the mercury 4.

We will now follow the course of the electric current when the load on the circuit is 90 greater than contracted for.

From m , the current passes through A , through wire 1, through solenoid coil B , wire 10, contact screw 7, wire 8, resistance F , wire 9, wire 6, binding screw E , binding screw m' 95 into the circuit. It must be noted that an excess of current through the solenoid disturbs the equilibrium of the scale beams $d. d.$ because this energy pulls down the solenoid armature, and consequently destroys the 100 normal circuit by raising the contact plunger 3 out of mercury 4, the current in that case has no alternative than to find its way through the resistance F , and this resistance, by the fact that it lowers the voltage, causes 105 the lamps back of same to be dimmed, but the moment this takes place, the energy in the solenoid coil is decreased, and the balance of the solenoid armature reinstated when the lamps will glow, and these phases 110 will be repeated until the load is made normal. It will be therefore evident that our

controller does not put out the lights and is an advantage over all devices, where the circuit is intermittently broken and connected. These make and break mechanism, we hereby 5 disclaim and

We claim as our invention:

1. In an electric controller, a main circuit, lights in the said circuit, a shunt circuit, a resistance in the said shunt circuit, an automatic cut out in said circuit, said cut out consisting of a solenoid, a hollow armature for said solenoid, a contact rod movably mounted inside of said hollow armature and means connecting said armature and contact rod, to 10 break the contact when a current above a predetermined strength is passing through the solenoid.

2. In a controller for electric circuits, a main circuit, a shunt circuit, a solenoid in the main circuit, a hollow armature for said solenoid, a pair of beams, a plunger contact rod passing through said hollow armature, connections between said beams and said armature, and connections between said beams 20 and said contact rod, the said beams being so balanced that when an excess of current operates the solenoid armature the main circuit will be broken and the current diverted through the resistance in the shunt circuit.

3. In a controller for electric circuits, a circuit conducting the current unobstructed, when the load is normal, an automatic resistance shunting device in said circuit consisting in solenoid, a hollow armature for said solenoid, a pair of beams connected to the 30 said armature, a plunger contact rod mounted to move inside of said hollow armature, and connecting links between said armature and beams, and between said beams and said contact rod, so balanced that the said rod 35 will be raised out of contact when an increased current causes the said armature to plunge further into said solenoid.

4. In a controller for electric circuits a solenoid through which the whole current 40 passes, a hollow solenoid armature, a contact rod movably mounted through said hollow armature, and means connecting said armature and said contact rod to raise said contact rod 45 out of contact, when the said armature is pulled further into said solenoid by an increased current.
